COMBINATION COLLAPSIBLE DRYING RACK
AND CONTAINER THEREFOR OR SIMILAR ARTICLE

Albert Spielman, 43 Grand St., Brooklyn, N.Y.

Filed Oct. 11, 1963, Ser. No. 76,950

Term of patent 14 years

(Cl. D49—1)

I claim:

The ornamental design for a combination collapsible drying rack and container therefor or similar article, as shown and described.
